ELECTRIC SWITCH

Alfred G. von Nermann, Seattle, Wash., assignor
to Trumbull Electric Company, Pacific Division,
Seattle, Wash., a corporation of Washington

Application August 16, 1933, Serial No. 685,329

5 Claims. (Cl. 206—58)

My invention relates to an electric safety switch and the general object of my invention is to provide an electric safety switch which is compact and simple in construction; reliable, efficient and safe in operation; not expensive to manufacture; easy to install and service and safe to handle due to the provision of safety features which are embodied in the construction of the switch and in the housing or receptacles for said switch.

Another object of the invention is to provide a simple and efficient switch which is built in the form of a compact unit and in which a plurality of these units are especially well adapted for grouping, in instances where more than one switch unit is used.

Another object of the invention is to provide an electric safety switch in which the fuse members and switch contact members are located in two separate compartments and in which access to the fuse compartment may be had without opening the compartment in which the contact members are located.

Another object of the invention is to provide an electric safety switch having safety features which make it impossible to open the cover of the fuse compartment except when the switch is in electrically open position and which further make it impossible to electrically close the switch until the cover of the fuse compartment has been closed.

Another object of the invention is to provide an advantageous arrangement of the several parts to the end that installation and wiring of the switch is facilitated.

A further object is to provide a switch of this nature in which no external metal cabinet or housing is used and in which the switch mechanism is assembled directly within a small and compact receptacle of insulating material which occupies very little space as compared to the usual switch cabinet of this type.

Other and more specific objects of the invention will be apparent from the following description taken in connection with the accompanying drawings.

In the drawings Figure 1 is a plan view of an electric safety switch constructed in accordance with my invention.

Fig. 2 is a longitudinal section of the same substantially on broken line 2—2 of Fig. 1.

Fig. 3 is a cross section substantially on broken line 3—3 of Fig. 2.

Fig. 4 is a detached perspective view of the cover for the fuses.

Fig. 5 is a detached plan view of a movable carriage member which carries the switch blades and the fuse clips.

Fig. 6 is a longitudinal section similar to Fig. 2 except that the switch is shown in an electrically open position and the cover of the fuse compartment is shown open to afford access to the fuses.

Fig. 7 is a longitudinal sectional view of the switch housing with internal parts removed to show the arrangement of trackways and grooves in said housing.

Fig. 8 is a sectional view through the carriage plate substantially on broken line 8—8 of Fig. 5.

Like reference numerals designate like parts throughout the several views.

In the construction of this switch I provide a rectangular housing, preferably formed in two halves 10 and 11 separable along the line 12 and secured together in assembled relation by screws 20 13. Each side wall of the housing is internally provided with a longitudinal groove or trackway 14 for the reception of pins or rollers 15 in the edges of a carriage plate 16 which is movable longitudinally within the housing. Preferably two of the pins 15 are provided at each edge of the carriage plate 16 adjacent the respective corners thereof and the said pins 15 are preferably slidable lengthwise in holes 17, Fig. 8, in the carriage plate and are urged outwardly by compression springs 18 whereby they may be pressed into the carriage plate to permit said carriage plate to be inserted into the housing without separating the two parts of the housing. When the carriage plate is properly assembled in the housing it may be moved lengthwise between the closed switch position shown in Fig. 2, to the open switch position shown in Fig. 6.

A box like fuse cover 20, having one open side, is hinged to the carriage plate 16 by hinge means 40 21 in such a manner that the carriage plate 16 forms a closure means for the open side of the box like cover. The sides of the cover member 20 are externally provided with lugs 22 which are longitudinally movable in grooves 23 in the sides of the housing 10—11 and which are positioned to register with notches 24 when the carriage plate 16 is in open switch position whereby the cover member 20 may be swung upwardly into an open position as shown in Fig. 6. The notches 24 are in flange portions 19 of the housing walls which overhang the grooves 23 and the cover 20 can be raised only when the lugs 22 are in alignment with the notches 24. This makes it impossible to open the cover 20 when the switch

is closed. The cover member 20 has an internal, medially disposed longitudinal partition 25 which divides said cover member into two compartments for the housing of two fuse members 26 which are each held by two spaced apart fuse clips 27 of the usual form. The fuse clips 27 are electrically connected with switch blades 28 by screws 29. The switch blades 28 are positioned on the opposite side of the carriage plate from the fuse clips 27 and the screws 29 also serve as a means for rigidly securing both the fuse clips 27 and the switch blades 28 to the carriage plate 16. Obviously more than two sets of fuse clips and switch blades may be provided side by side on the carriage plate if desired. The front end of the cover 20 may have a flange 30 thereon which is provided with a notch 31 through which an eye member 32 may extend whereby the cover member 20 may be fastened with a seal or may be locked in a closed position as by insertion of the shackle of a padlock, not shown, through the eye member. The ends of the cover member 20 may further be provided with flanges 33 which facilitate grasping said cover member for the purpose of moving the switch into open or closed position, said cover member thus serving as a hand hold.

Two bifurcated spring metal switch jaws 34 and 35 are secured to an end wall of the housing 10-11 as by screws 36 and two other similar switch jaws 37 and 38 are secured, by screws 39, to a bar or member 40 which extends crosswise of the housing 10-11 approximately mid way between the two ends thereof. The switch jaws 34, 35, 37 and 38 are positioned in alignment with the switch blades 28 whereby the switch blades 28 may enter between said jaws when the several parts are in the closed switch position shown in Fig. 2.

The switch jaw 34 may be electrically connected by an L shaped conductor member 41 with a main electrical conductor 42 through which current is supplied. In a similar manner the switch jaw 35 may be connected by L shaped conductor member 43 with another main electrical conductor 44. The two main electrical conductors 42 and 44 are illustrated as bus bars which extend crosswise of the switch housing and which are of advantage where a plurality of these switches are placed side by side close to each other. Obviously circuit wires may be used instead of bus bars if desired. The other two switch jaws 37 and 38 are electrically connected respectively with L shaped conductor members 45 and 46 which are connected by terminal clips 47 and 48 with circuit wires 49 and 50. Provision is thus made for electrically connecting or electrically disconnecting circuit wire 49 with respect to bus bar 42 and circuit wire 50 with respect to bus bar 44 through the closing and opening of the switch.

The side walls of the housing 10-11 are grooved as indicated at 51 in Fig. 8, for the reception of sheets or plates of insulating material 52 whereby the several bus bars and conductor members are more effectively insulated from each other. Plates 53 of insulating material are also provided in the housing 10-11 just below the carriage plate 16 whereby access is prevented to that portion of the housing in which the switch mechanism proper is located.

In the operation of this switch, when the carriage plate 16 is in the position shown in Fig. 2 the switch blades 28 will be in engagement with the switch jaws 34, 35, 37 and 38 and the wires 49

and 50 will be electrically connected respectively with the bus bars 42 and 44 through the fuse members 26. When the switch is in this electrically closed position the cover 20 of the fuse compartment can not be opened due to the fact that lugs 22 on the outer sides of said cover 20 are held down by the flange members which overhang the grooves 23. This makes it necessary to open the switch before access can be had to the fuse members. The switch is moved between the open and closed positions by grasping the cover member 20, which forms a convenient hand hold. When the carriage plate 16 is in the position shown in Fig. 6, the switch blades 28 will be withdrawn from the switch jaws and the switch will be open. In this open switch position the lugs 22 on the cover 20 will be positioned so that they will pass through the notches 24 and the cover 20 may be opened or closed at will. If an attempt is made to close the switch while the cover 20 is in the open position shown in Fig. 6, said cover will strike against the end of the housing and block the closing of the switch. This makes it necessary to close the cover 20 before the switch can be closed.

The bus bars 42 and 44 extending crosswise of the switch are preferably used where a plurality of switches are positioned side by side and all connected with the same bus bars.

By placing the fuse members 26 in the compartment directly opposite to the switch mechanism and by providing for a sliding movement of the carriage and switch blades instead of a swinging movement, I am able to provide a very compact switch and one that can be installed in a very small space. This is a very advantageous feature especially where several switches are required in one installation and where space is limited.

The foregoing description and accompanying drawings clearly disclose a preferred embodiment of my invention but it will be understood that this disclosure is merely illustrative and that such changes in the invention may be made as are fairly within the scope and spirit of the following claims.

I claim:

1. In an electric safety switch of the class described, a housing of substantial depth, a carriage plate guided for endwise movement in said housing substantially midway of the depth thereof, switch blades mounted on one side of said carriage plate, fuse clips mounted on the other side of said carriage plate and electrically connected with said switch blades, switch jaws positioned for engagement by said switch blades, fuse members supported in said fuse clips, a box like cover pivotally mounted on said carriage plate and disposed partially within said housing, said box like cover having one open side positioned adjacent the carriage plate whereby said box like cover may close over said fuse members, partition means in said cover positioned to enter between said fuse members and provide a separate compartment for each fuse member, and cover holding devices operatively connecting the cover and the housing and holding adjacent sides of the the cover closed when the switch is in electrically closed position.

2. In an electric safety switch of the class described, a housing, a carriage plate guided for endwise movement in said housing, switch blades mounted on one side of said carriage plate, fuse clips mounted on the other side of said carriage

- plate and electrically connected with said switch blades, switch jaws positioned for engagement by said switch blades, fuse members supported in said fuse clips, a box like cover pivotally mounted on said carriage plate, said box like cover having one open side positioned adjacent the carriage plate whereby said box cover may close over said fuse members, said housing having grooves parallel to the plane of movement of said carriage plate and having notches which intersect said grooves, and lug members on the sides of said cover arranged to extend into said grooves and positioned in registration with said notches when said switch is in electrically open position whereby said cover may be opened and closed when said switch is in electrically open position but will be held closed by engagement of said lug members within said grooves when said switch is in electrically closed position.
3. In an electric safety switch of the class described, a housing having longitudinally extending grooves in the side walls thereof, a carriage plate positioned within said housing, pins protruding from the sides of said carriage plate into said grooves whereby said carriage plate is guided for endwise movement in said housing, switch blades mounted on one side of said carriage plate, fuse clips mounted on the other side of said carriage plate and electrically connected with said switch blades, switch jaws positioned for electrical contact by said switch blades, and a box like cover hinged to said carriage plate and having an open side adjacent said carriage plate, said cover forming a receptacle for said fuse members and further forming a hand hold for the operation of said switch.
4. In an electric safety switch of the class described, a housing having longitudinally extending grooves in the side walls thereof, a carriage plate positioned within said housing, pins protruding from the sides of said carriage plate into said grooves whereby said carriage plate is guided for endwise movement in said housing, switch blades mounted on one side of said carriage plate and electrically connected with said switch blades, fuse members supported in said fuse clips, a box like cover pivotally mounted on said carriage plate and having one open side positioned adjacent the carriage plate whereby said box cover may close over said fuse members, said housing having grooves parallel to the plane of movement of said carriage plate and having notches which intersect said grooves, and lug members on the sides of said cover arranged to extend into said grooves and positioned in registration with said notches when said switch is in electrically open position whereby said cover may be opened and closed when said switch is in electrically open position but will be held closed by engagement of said lug members within said grooves when said switch is in electrically closed position.
5. In an electric safety switch of the class described, a rectangular housing having longitudinal grooves in the inner sides of the side walls thereof, a carriage plate of a width substantially equal to the interior width of said housing and of a length less than the interior length of the housing disposed within said housing, means guiding said carriage plate for endwise movement in said housing, switch jaws mounted in said housing on one side of said carriage plate, electrical conductors connected with said switch jaws, switch blades secured to said carriage plate and movable with said carriage plate into electrically connected or electrically disconnected positions relative to said switch jaws, fuse clips mounted on the sides of said carriage plate opposite to said switch blades and electrically connected with said switch blades, fuse members connected with said fuse clips, a box like cover hinged to said carriage plate and forming a receptacle for said fuse clips and fuse members, and means controlling the opening and closing of said cover member, said cover controlling means being governed by the positioning of said carriage plate.

ALFRED G. VON NORMANN.
